CLAIM

The ornamental design for a moving light projector, as shown and described.

DESCRIPTION

FIG. 1 is a front and side perspective view of a moving light projector showing our new design according to one embodiment;

FIG. 2 is a front elevation view thereof;

FIG. 3 is a left side elevation view thereof;

FIG. 4 is right side elevation view thereof;

FIG. 5 is a rear elevation view thereof;

FIG. 6 is a top plan view thereof; and,

FIG. 7 is a bottom plan view thereof.

The broken line disclosure represents portions of the projector which form no part of the claimed design.
